UNITED STATES PATENT OFFICE

2,363,524

GASKET CONSTRUCTION

August W. L. Hartbauer, Chicago, Ill.

Application March 24, 1941, Serial No. 384,917

5 Claims. (Cl. 20—69)

This invention relates to a gasket and means for joining said gasket units of two or more pieces, preferably adapted for application to railway car hatch and door arrangements.

The construction herein shown is an improvement on that shown in my prior Patent No. 2,189,795, dated February 13, 1940. The features of improvement are in the shape and disposition of the reinforcement and in its relation to the corners of the gasket. Much is added to the adaptability of the gasket for general use, the features of simplification of application and of flexibility in use being pronounced.

As I pointed out in my said prior patent, the hatch closure and door arrangements in general use in railway cars employ the plug design. In these forms of closures it is absolutely necessary to provide some form of perimeter edging that will yield, to compensate for variance in construction, to insure the seating of the plug or closure in ultimate closed position in both arrangements. The yielding edges of the hatch plug are usually formed by upholstering the edges over a foundation of curled hair or the like. The yielding edges of the door parts are usually formed with a wood slab spring actuated foundation and covered with a felt form of padding and then upholstered to complete the application. The door arrangement yielding edging is not continuous, being applied in sections to either the car door parts or the bar body parts. It is necessary that as the door arrangement units are moved to closed position that the yielding or sealing elements of the door and body register to insure an uninterrupted and continuous contact.

The construction shown in my prior patent accomplishes the main objects sought, but it leaves something to be desired in the matter of attachment, and, in an annularly complete gasket such as used on hatch doors, in the matter of flexibility at the corners or angles. These features are improved in the construction here disclosed.

In the drawings:

Fig. 1 is a plan view showing the contour of the cloth which covers the core and forms the outer surface of the gasket and which shows the bifurcated end of the cloth and the slits employed for angle corner assembly.

Fig. 2 is a plan view showing the contour of the cloth which covers the core and forms the outer surface of the gasket and shows the tabs and slits employed for square corner assembly.

Fig. 3 is a plan view showing the contour of

the sponge rubber cores for angular corner assembly.

Fig. 4 is a plan view showing the rubber cores with butt ends for square corner assembly.

5 Fig. 5 is an enlarged plan view showing the butt end of the sponge rubber cores with the integral triangular shaped corner filler portion moved into position for assembly.

Fig. 6 is a plan view showing the assembly 10 of the cloth and the sponge rubber cores for angle type of corner assembly of the units.

Fig. 7 is a diagrammatic end view showing two sponge rubber cores assembled on the covering cloth.

15 Fig. 8 is a diagrammatic end view showing an alternate method of using one sponge rubber core assembled on the cloth covering.

Fig. 9 is a plan view showing the assembly of 20 the cloth and the sponge rubber cores for square type corner assembly.

Fig. 10 shows a section of the preferred form 25 of wire reinforcing used in the gasket units.

Fig. 11 shows a section of an alternate kind 30 of perforated metal or composition reinforcing that may be used in the gasket units.

Fig. 12 shows a section of still another kind of 35 expanded metal reinforcing which may be used in the gasket units.

Fig. 13 is a diagrammatic end elevation showing 40 the preferred method of assembling the metal reinforcing shown in Fig. 10 with the folded gasket section Fig. 7.

Fig. 14 is a diagrammatic end elevation showing 45 the folded gasket sections completely formed with the metal reinforcement encased by both edges of the cloth.

Fig. 15 is a diagrammatic end elevation showing 50 the alternate method of encasing the reinforcing member by utilizing one marginal portion of the cloth and encasing the edge of the core with opposite marginal cloth portion.

Fig. 16 is a diagrammatic end elevation showing 55 the encased reinforcing member Fig. 15 moved into contact with the edge of the gasket.

Fig. 17 is a plan view of the gasket unit for 60 angle corner assembly showing the metal reinforcing by dash lines.

Fig. 18 is a plan view of the gasket unit for 65 square corner assembly showing the metal reinforcing by dash lines.

Fig. 19 shows the contour and the slits in the 70 cloth corner gusset with either angular or square corner assembly.

Fig. 20 is a plan view of the angular corner 75 assembly looking at the contact surface of the

gasket and shows the ends of the reinforced flanges spaced apart providing flexible compensating corner gasket section.

Fig. 21 is a plan view of the angular corner assembly looking at the bearing surface of the gasket.

Fig. 22 is a plan view of the square corner assembly looking at the contact surface of the gasket and shows the ends of the reinforced flanges spaced apart providing flexible compensating corner gasket section.

Fig. 23 is a plan view of the corner assembly looking at the bearing surface of the gasket.

Fig. 24 is a cross sectional view on line B—B in Fig. 20 and shows the flexing corner section encased by the gusset Fig. 19.

Fig. 25 is a plan view of a hatch closure gasket assembly showing four gasket units in applied position.

Fig. 26 is a cross sectional view on line C—C Fig. 25 and shows the flexing of the gasket.

Fig. 27 is a cross sectional view showing the gasket in service position as applied to a refrigerator car door arrangement.

Fig. 28 is an isometric cross sectional view of the cloth covering cemented together with the metal reinforcing therebetween on the line A—A in Fig. 14.

Many of the features disclosed herein are similar to those shown in my prior patent and not illustrated in order to clarify the features of novelty.

In constructing the gasket units of the invention the cloth covering 1 is suitably treated and waterproofed on one side only with cementitious or other suitable material, and then cut to the width and contour preferably as shown in Figs. 1 and 2. The cloth covering 1 for the angular corner assembly is provided with a square or butt end 2. The parallel edges or marginal portions 3 and 4 are relatively long and are gauged as to their width and length by the dimensions of the notches 5, 6, 7 and 8. The opposite end of the cloth covering 1 is bifurcated and slit to form the tabs 9, 10, 11, 12 and 13 the sections 9 and 13 also constituting relatively short marginal portions of the cloth covering 1. The short marginal portions 9 and 13 are in longitudinal alignment with the long portions 3 and 4.

The cloth covering 14 for the square corner assembly is provided with a square or butt end 15. The parallel edges or marginal portions 16 and 17 are relatively long and are gauged as to their width and length by the notches 18, 19, 20 and 21. The opposite end of the cloth covering is offset, the slit 22 forming the tabs 23, 24 and 25. The short sections 23 and 25 are in longitudinal alignment with the long marginal portions 16 and 17.

Gauging the width of the parallel edge portions 3 and 4 as shown in Fig. 1, and the parallel edges 16 and 17 shown in Fig. 2 is necessary to provide integral cloth covering to encase the reinforcements shown in Fig. 10 and those shown Figs. 11 and 12. The length of the reinforcing wire is determined by the slots 5, 6, 7 and 8 in Fig. 1 and by the slots 18, 19, 20 and 22 in Fig. 2. Fig. 3 shows the sponge rubber cores 29 and 30 for the angular type of corner assembly, each provided with an integral triangular shaped corner filler tab 26 also shown in Fig. 5 and is adapted to be moved to the position indicated by full lines in Fig. 5 and in alignment with the butt end 27 of the cores 29 and 30 to facilitate the assembly of the gasket units. The opposite ends

of the cores 29 and 30 are contoured to register with the bifurcated sections of the cloth shown in Fig. 1. One side of the rubber cores 29 and 30 is coated with cement 1a and the cores 29 and 30 are placed on the cloth 1 contacting the treated surface of the cloth, thereby forming the flat sections of the gasket units as shown in Figs. 6 and 7.

Fig. 8 shows an alternate form of gasket unit section in which only one rubber core 30a is used, the contour being the same as the core 30 in Fig. 6. The thickness of the core 30a is equal to the combined thickness of the cores 29 and 30 shown in Fig. 7. The core 30a is cemented to the cloth 1 thereby forming the flat section of the gasket unit as shown in Fig. 8.

Fig. 4 shows the sponge rubber cores 31 and 32 for square assembly with butt ends 28. One side of the cores 31 and 32 is coated with cement 1a and the cores are placed on the cloth 14 Fig. 9 contacting the treated surface of the cloth 14, thereby forming the flat sections of the gasket units as shown in Figs. 7 and 9.

To assemble the gasket units 37 and 38, fold the assemblies Figs. 6 and 9 until the surfaces of the rubber cores 29 and 30 in Fig. 6 and the surfaces of the cores 31 and 32 in Fig. 9 are in contact as shown Fig. 13.

The assembly is continued by placing the angular formed reinforcing 33 Fig. 10 or other suitable reinforcements such as 33a Fig. 11 and 33b Fig. 12 with the flange 34 in contact with the edges of the cores 29 and 30 and the cores 31 and 32 shown in Figs. 6 and 9. The flange 35 of the reinforcing 33 Fig. 10 contacting the marginal cloth portions 3 and 16 shown Figs. 6 and 9 and the assembly as shown Fig. 13.

To complete the gasket units 37 and 38 fold the marginal edges 4 and 17 Figs. 6 and 9 to encase the reinforcing wire 33 and forming the attachment flange 36 as shown in Fig. 14.

In the alternate method shown in Figs. 15 and 16 fold the cloth assemblies shown in Figs. 6 and 9 until the surfaces of the rubber cores 29 and 30 Fig. 6 or the rubber cores 31 and 32 are in contact as shown in Fig. 15. Encase the edges of said cores with the marginal edge 4 in Fig. 6 or marginal edge 17 in Fig. 9 and join said marginal edges with the marginal edges 3 and 6 in Figs. 6 and 9.

To complete the assembly encase the angular shaped reinforcing 33 with the marginal edges 4 Fig. 6 or 17 Fig. 9 and then folding the marginal edges 4 or 17 Figs. 6 and 9 to place the encased reinforcing flange 34 in contact with the edge of the cores as shown Fig. 16.

The exposed surface of the cloth and the reinforcing wire having been given a coat of cement 1a will bond and amalgamate these parts together with the reinforcing wire as pressure is applied and as shown Fig. 28.

The meshes of the reinforcing wire 33 offer unrestricted opposed contact surface of the cloth 1 or 14 as a means of encasing said wire reinforcement 33 within the structures as shown Figs. 14, 16 and 28, completing the gasket units 37 Fig. 17 and Fig. 18 for unit 38.

In order to join the gasket units 37 Fig. 17 and also the units 38 for angular corner assembly Figs. 20 and 21, or square corner assembly Figs. 22 and 23, the butt end of one unit 37 is joined with the edges of the other unit, cement 1a having been applied to the respective surfaces in advance. The parts are then joined together to form the joint 39 shown in Figs. 20 and 22. To

complete the assembly of the angle corner type shown Figs. 20 and 21, the tabs 9 and 13 are brought to binding contact with the edges of the units and also a portion of the edges of the rubber cores. The flange 10 is joined with the flange 12 in Fig. 24 forming the flange 40 which encases a portion of the tabs 9 and 13 and also the ends of the cores as shown in Figs. 20 and 24.

The inner angular edges of the cores are encased by a gusset 41, Fig. 19 by joining the tabs 42 with the edges of the units 37 and folding the gussets 41 in line with the slits 43 the tabs 44 and the folded portion are then joined with the contact surface of the units whereby to seal and reinforce the corner assembly. To complete the square corner assembly Figs. 22 and 23 the tabs 23, 24 and 25 are brought into binding contact with the surfaces and the edge of the assembled units. The inner edges of the cores are encased by the gusset 41 by joining the tabs 42 with the edges of the units and folding the gusset 41 in line with the slits 43 the tabs 44 and the folded portion are then joined with the contact surface of the units whereby to seal and reinforce the corner assembly.

The assembled gasket generally designated as 45 is completed when the unit sections are joined at the corners as shown Fig. 25.

In some instances and especially pertaining to door applications, assembly of the units may not be required, in these instances the units are applied separately and adapted to move into contact as the door is moved to the fully closed position, the rubber core of the gasket section yielding to compensate for structural variance to insure proper seal.

Figs. 25 and 26 show the hatch closure in which the frame sections 46 are joined together at the corners in a substantial manner. The frame sections 46 are shaped to provide a limiting surface 47 and the gasket bearing surface 48. The assembled frame sections 46 are secured to the metal cover 49 with bolts or screws, the lining 50 is nailed to the frame members 46. The resultant space 51 between the frame members and the plate 49 is filled with suitable insulating material.

The assembled gasket 45 is applied to the bearing surface 48 and secured thereto by a series of nails 52 in the retaining flanges 36, best shown in Fig. 26.

The extending flange 34 of the wire reinforcing best shown Fig. 14 is rigid and contacts the inner edges of the gasket rubber core sections to hold the gasket in nominal contact with the surface 48 to which the gasket 45 is fastened best shown in Fig. 26 and provides the resistance which makes possible the flexing of the gasket sections as shown in dot and dash lines Fig. 26. Therefore shocks due to momentary sticking of the gasket surface resulting from climatic or other conditions are absorbed by the pliable gasket section and not transmitted to the fastening means of the gasket. Thereby preventing loosening of the fastening element or damage to the gasket in the service for which it is designed.

In Fig. 27 the gasket 45 or a unit thereof is

applied to the peripheral edge 53 of the door section 54 with nails 52. The peripheral edge 55 of the door section 56 contacting the gasket 45 or unit thereof in the full closed position of the doors as shown.

What I claim and desire to secure by Letters Patent is:

1. In a gasket, the combination of a core of resilient material, metal reinforcement, L-shaped in cross section, one leg lying against a side edge of said core and the other leg extending substantially parallel to and in a plane with one face of said core, and fabric enclosing said core and reinforcement and adhesively secured to the parallel leg of said reinforcement.
2. In a gasket, the combination of a flat sponge rubber core, an L-shaped metal reinforcement, one flange of the reinforcement lying against one side edge of the core and the other flange lying parallel to and substantially in the plane of one flat side of the core and extending laterally therefrom and fabric enclosing said core and reinforcement whereby when said gasket is secured to a support by fastening means through said lateral flange, one edge of said gasket is free.
3. In a gasket, the combination of a core composed of a plurality of sections of sponge rubber, a section of fabric surrounding said core and having extended marginal edges, an angular metal reinforcement, one flange of the angle lying against a side edge of the core and one flange lying parallel to and substantially in the plane of a side of the core and projecting laterally therefrom, the marginal edges of said fabric overlying said reinforcement and adhesively secured thereto and to each other.
4. In an annularly complete gasket, the combination of a core composed of abutting sections, combined reinforcing and attachment strips extending throughout the length of the straight portions of the gasket, said reinforcement comprising metal strips of angular cross-section, one flange lying against an inside edge of the gasket, the other flange projecting laterally inwardly parallel to the bottom face of the gasket, and fabric enclosing said core and reinforcement, said reinforcement being interrupted at the corner angles of the gasket whereby to insure freedom of movement of the gasket at such corners.
5. In an annularly complete gasket having straight portions and angular portions, the combination of a core composed of abutting sections, combined reinforcing and attachment strips extending throughout the length of the straight portions of the gasket, said reinforcement comprising metal strips of angular cross-section, one flange lying against an edge of the gasket, the other flange projecting laterally parallel to the bottom face of the gasket, and fabric enclosing said core and reinforcement, extending portions of said fabric being in overlapped secured connection at the corner angles of the gasket providing a connection for the core, and said reinforcement being interrupted at the corner angles of the gasket whereby to insure freedom of movement of the gasket at such corners.

AUGUST W. L. HARTBAUER.
